[57] ABSTRACT

In a cold cathode display apparatus of the class comprising a plurality of opposed electrodes and a transparent envelope containing the electrodes and filled with a luminous inert gas, there are provided a plurality of display units in the envelope. Each display unit comprises a plurality of first electrodes, a plurality of second electrodes, insulator spacer means disposed between the first and second electrodes, the spacer means being provided with a plurality of perforations which define independent discharge cells between the first and second electrodes, a plurality of starting anode electrodes respectively contained in the discharge cells, a plurality of starting cathode electrodes respectively contained in the discharge cells, a plurality of resistors respectively connected to the second electrodes and a plurality of erasing electrodes disposed near the first electrodes. The plurality of display units are arranged in the direction of lines, the erasing electrodes of respective display units are arranged in the direction of lines, and the first electrodes and the starting anode electrodes of respective display units are arranged in the direction of columns. The starting cathode electrodes and the second electrodes of respective display units are arranged in the direction of both lines and columns.

COLD CATHODE DISCHARGE DISPLAY APPARATUS MANIFESTING MEMORY ACTION

BACKGROUND OF THE INVENTION

This invention relates to an improved cold cathode discharge display apparatus, and more particularly to cold cathode discharge display apparatus manifesting memory action and capable of erasing and rewriting a pattern at any desired position.

A conventional cold cathode discharge display apparatus comprises a pair of opposed electrodes disposed in an envelope sealed with a luminous inert gas such as neon or argon gas and an electric discharge is established between the electrodes to luminescence the inert gas thereby displaying a desired pattern.

In the conventional cold cathode discharge display apparatus sold under the trade marks Elfin and Plantron a plurality of display units, each consisting of a plurality of segment electrodes, and a counter electrode disposed to oppose the segment electrodes with a predetermined spacing therebetween, are disposed side by side in the same envelope. Such display apparatus is used to display patterns of a plurality of digits by selectively operating the display units on the time division basis at such a high speed that does not cause flickering.

However, such a display apparatus lacks memory function so that it is necessary to provide an independent memory device thereby increasing the cost of manufacturing and complicating the construction of the display apparatus.

Although a memory action can be provided for the display apparatus by utilizing plasma luminescence, the plasma luminescence requires a high voltage high frequency AC source operating at a voltage of 200 V and at a frequency of 200 KHz. Moreover in such display apparatus it is impossible to erase a desired memory.

SUMMARY OF THE INVENTION

Accordingly, it is an object of this invention is to provide an improved cold cathode discharge display apparatus of compact construction and capable of manifesting memory function without providing an independent external memory device.

A further object of this invention is to provide an improved cold cathode discharge display apparatus capable of erasing and rewriting a pattern at any desired position.

According to this invention there is provided a cold cathode discharge display apparatus of the class comprising a plurality of opposed electrodes and an envelope containing said electrodes and filled with a luminous inert gas, at least a portion of the envelope being transparent, characterized in that there are provided a plurality of display units in the envelope, that each of the display units comprises a plurality of first electrodes, a plurality of second electrodes, insulative spacer means disposed between the first and second electrodes, the spacer means being provided with a plurality of perforations which define independent discharge cells between the first and second electrodes, a plurality of starting anode electrodes respectively contained in the discharge cells, a plurality of starting cathode electrodes respectively contained in the discharge cells, a plurality of resistors connected to the second electrodes, and a plurality of erasing electrodes disposed near the first electrodes, that the plurality of dis-

play units are arranged in the direction of lines, that the erasing electrodes of respective display units are arranged in the direction of lines, that the first electrode and the starting anode electrodes of respective display units are arranged in the direction of columns and that the starting cathode electrodes and the second electrodes of respective display units are arranged in the direction of both lines and columns.

BRIEF DESCRIPTION OF THE DRAWINGS

The invention can be more fully understood from the following detailed description taken in conjunction with the accompanying drawings in which:

FIG. 1 shows an exploded perspective view of the various component elements of a cold cathode discharge display apparatus constructed according to the teaching of the invention;

FIG. 2 is a plan view showing the starting cathode substrate utilized in the display apparatus shown in FIG. 1;

FIG. 3 shows an enlarged sectional view of the cathode substrate employed in the display apparatus shown in FIG. 1 and

FIG. 4 shows an equivalent circuit of the cold cathode discharge display apparatus shown in FIG. 1.

DESCRIPTION OF THE PREFERRED EMBODIMENT

Referring not to FIG. 1 of the accompanying drawings, a cold cathode discharge display apparatus 1 shown therein comprises upper and lower substrates 2 and 3 made of transparent material such as glass and forming a portion of the envelope which is formed in a manner to be described later. Between the upper and lower substrates are disposed a plurality of parallel erasing anodes 4a through 4d, one for each line, a plurality of parallel anode electrodes 5a through 5d, one for each column, a plurality of parallel starting anodes 6a through 6d, also one for each column, a starting cathode plate 7, and a cathode substrate 8. Insulator spacers 9 through 12 are interposed respectively between erasing anodes and anode electrodes, between anode electrodes and starting anodes, between the starting anode and the starting cathode plate and between the starting cathode plate and the cathode substrate. Each of the electrodes and spacers interposed between the upper and lower transparent substrates 2 and 3 are provided with a plurality of groups of perforations 13 which are arranged in aligned matrixes. The inner walls of the perforations of the starting cathode plate 7 are provided with through hole platings, each acting as a starting cathode electrode 14. Alternate starting cathode electrodes 14 on each line are connected to terminals 15 on the opposite ends of the plate 7, as shown in FIG. 2.

As shown in FIG. 3, the cathode substrate 8 comprises a sheet of insulator provided with a plurality of groups of perforations 13 which are arranged in matrixes and solid state resistors 16 formed by compressing a powder of glass or ceramic are contained in respective perforations 13. The upper surfaces of the resistors 16 confronting the anode electrodes 5a through 5d are coated with electrodes 17 which are formed by plating nickel, for example, whereas the lower surfaces of the resistors 16 are electrically connected to a thin conductive sheet 18 having substantially the same coefficient of thermal expansion as the lower substrate 3

made of glass or ceramic, the thin sheet 18 serving as a common lead wire for the resistors 16.

Various electrodes and spacers described above are superposed one upon the other between the upper and lower transparent substrates 2 and 3 to form a lamination and the periphery of the lamination is sealed hermetically with frit glass or the like to form an envelope. After evacuation, the interior of the envelope is filled with a luminous inert gas such as argon gas or neon gas thereby completing a cold cathode discharge display apparatus with four lines and four columns. As shown in FIG. 1, erasing anodes 4a - 4d, anode electrodes 5a - 5d and starting anode electrodes 6a - 6d are provided with terminals 19a - 19d, 20a - 20d and 21a - 21d, respectively, extending through the side walls of the envelope formed as above described.

FIG. 4 shows an equivalent circuit for four columns and two lines of the cold cathode discharge display apparatus described hereinabove. In FIG. 4, the component elements corresponding to those shown in FIG. 1 are designated by the same reference numerals. There are also provided driving members 22a and 22b for starting cathodes, protective resistors 23a through 23n and 24a through 24n for limiting the current flowing through the starting cathodes, input terminals 25a and 25b for driving members 22a and 22b, respectively. The first and second lines are designated by H₁ and H₂ and the first to fourth columns by V₁ through V₄, respectively. The relative spacings between anode electrodes 5a - 5d, starting anode electrodes 6a - 6d, starting cathode electrode 14 and cathode electrode 17 are selected to satisfy the following conditions:

A. The breakdown or discharge initiating voltage between the anode and cathode electrode is higher than the breakdown voltage between the starting anode and the starting cathode and the breakdown voltage between the anode and the cathode electrode when a discharge is being maintained between the starting anode and the starting cathode is lower than the voltage impressed across the anode and cathode electrodes.

B. The discharge sustaining voltage between the starting anode and the starting cathode electrode is higher than the discharge sustaining voltage between the anode and cathode electrodes.

C. The voltage relations between the erasing anode and the cathode electrode are made to be substantially the same as those between the anode and cathode electrodes.

Typical values of these voltages are as follows:

Breakdown voltage between the anode and cathode electrode—200 V

Discharge sustaining voltage between the anode and cathode electrodes — 130 V

Breakdown voltage between the starting anode and the starting cathode—190 V

Discharge sustaining voltage between the starting anode and the starting cathode—180 V

In operation, a voltage lower than the breakdown voltage 200 V is impressed across anode electrodes 5a - 5d and cathode electrode 14. More particularly, a voltage of +100 V is impressed upon respective anode terminals 20a - 20d whereas a voltage of -50 V is impressed upon the cathode electrode. Upon application of an input signal upon input terminal 25a, the driving member 22a operates to select an appropriate ones of the starting cathode electrodes 14a through 14a corresponding to the pattern information contained in

the input signal whereby a pulse signal of -50 V is applied to the selected starting cathode electrode through corresponding one of resistors 23a through 23n. Concurrently therewith, a pulse signal of +150 V is impressed upon the terminal 21a of the starting anode to increase the potential difference between the starting anode and the starting cathode to 200 V which is higher than the breakdown voltage (190 V) between these electrodes. As a result, an electric discharge is established between a selected starting cathode, for example, 14a, positioned at the cross-point between the first line H₁ and the first column V₁ and starting anode 6a. Once the discharge is established between the selected starting anode and the starting cathode, the voltage drop between these electrodes decreases to a value lower than the voltage 150 V which has already been applied across corresponding anode electrode 5a and cathode electrode 17a so that the discharge will be automatically transferred to between these anode and cathode electrodes from between starting anode 6a and starting cathode 14a.

In the same manner, when a voltage is impressed across input terminal 25a and terminal 21b for the starting anode, an electric discharge is established between a selected one of the starting cathodes 14a through 14n and the starting anode 6b and this discharge is transferred to between a selected one of the cathode electrodes 17a through 17n and anode electrode 5b thereby displaying the desired pattern at the cross-point between the first line H₁ and the second column V₂. During the above described operation, when a voltage is applied to a selected one of the starting electrodes 14a through 14n, this voltage is also applied to the starting cathode 14a through 14n of the other display units. However, since voltage is not being applied upon the starting anode electrodes of the other display units, only the desired display unit wherein a synchronized voltage has been applied across the selected one of the starting anodes 6a through 6d and the starting cathodes 14a through 14n displays the desired pattern and other display units are not effected. For this reason, the pattern displayed in this manner will be continuously displayed even after the termination of the input signal impressed across the selected starting cathode and starting anode. This means that the novel display apparatus has a memory action. In this manner, all patterns are successively displayed. When the display of all patterns is completed if there is any erroneous display in any display unit, for example a display unit at the cross-point between the first line H₁ and the second column V₂, such an erroneous display can be corrected in the following manner.

First, a voltage equal to the voltage that has been applied to the selected one of the anodes 5a through 5d is impressed upon erasing anode 19b other than the erasing anode 19a which corresponds to the first line on which the error has occurred. Then, the voltage is removed from the anode terminal 20b corresponding to the second column on which the error has occurred. Under these conditions, the voltages are removed from the erasing anode 4a and anode 5b of only the display unit corresponding to the cross-point between the first line H₁ and the second column V₂. In the other display units, however, since the voltage is being impressed upon the erasing anode 19b or either one of the anode 5a, 5c and 5d, a discharge is sustained between an electrode impressed with this voltage and a cathode. By this

operation it is possible to readily erase the pattern displayed at any desired display unit. To write again the pattern in the erased display unit, above described predetermined voltage is impressed across the starting anode 6b and the selected one of the starting cathodes 14a through 14n.

Although in the illustrated embodiment the erasing anodes are disposed to the outside of the anode electrodes, the exact position of the erasing anodes are immaterial provided that they are located close to the anodes. Further, although a positive potential was applied to a plurality of electrodes which are arranged in a matrix to cause them to operate as cathode electrodes and a positive potential was applied to the electrodes in respective display units to cause them to operate as anode electrodes, it should be understood that the polarities of these potentials may be reversed.

Thus, it will be clear that the invention provides a new and improved cold cathode discharge display apparatus of compact construction capable of manifesting memory action, that is a display apparatus capably of continuously displaying a pattern without using an expensive external memory device. Moreover, in the novel display apparatus it is possible to readily erase any desired or erroneous pattern and rewrite it.

While the invention has been shown and described in terms of a preferred embodiment thereof, it should be understood that many changes and modifications are obvious to one skilled in the art without departing from the true spirit and scope of the invention as defined in the appended claims.

What is claimed is:

1. A cold cathode discharge display apparatus manifesting memory action comprising a plurality of display units, each including a plurality of first anode electrodes, a plurality of second cathode electrodes, insulative spacer means disposed between said first and second electrodes, said spacer means being provided with a plurality of perforations which define independent discharge cells between said first and second electrodes, a plurality of starting anode electrodes respectively contained in said discharge cells, a plurality of starting cathode electrodes respectively contained in said discharge cells, a plurality of resistors respectively connected to said second electrodes, a plurality of eras-

ing electrodes disposed near said first electrodes, and an envelope containing said plurality of display units, at least a portion of said envelope being transparent, said plurality of display units being arranged in the direction of lines, said erasing electrodes of respective display units being arranged in the direction of lines, said first electrodes and said starting electrodes of respective display units being arranged in the direction of columns, and said starting cathode electrodes and said second electrodes of respective display units being arranged in the directions of both lines and columns.

2. The display apparatus according to claim 1 wherein said erasing anodes, said first electrodes, said starting anodes, said starting cathodes and said second electrodes of each display units are provided with a plurality of perforations respectively aligned with the perforations of said spacer means, said perforations being arranged in a plurality of matrixes.

3. The display apparatus according to claim 1 wherein said spacer means comprises a plurality of perforated insulator sheets which are respectively interposed between said erasing anode electrodes and said first electrodes, between said first electrodes and said starting anode electrodes, between said starting anode electrodes and said starting cathodes electrodes, and between said starting cathode electrodes and said second electrodes and wherein the perforations of said plurality of insulator sheets are in alignment with those of said erasing anode electrodes, first electrodes, starting anode electrodes, starting cathode electrodes and said second electrodes.

4. The display apparatus according to claim 1 wherein said second electrodes comprises an insulator sheet provided with a plurality of perforations which are grouped into a plurality of matrixes, a plurality of resistors contained in respective perforations, and thin metal layers applied on one ends of said resistors.

5. The display apparatus according to claim 1 wherein said component elements of each display units are superposed one upon the other between a pair of transparent substrate to form a lamination and the periphery of said lamination is hermetically sealed to form said laminations.
